UNITED STATES PATENT OFFICE.

FREDERICK W. SUTTERLE, JR., OF SHANGHAI, CHINA.

ATTACHMENT FOR TYPE-WRITERS.

1,169,887.

Specification of Letters Patent.

Patented Feb. 1, 1916.

Application filed January 30, 1915. Serial No. 5,320.

To all whom it may concern:

Be it known that I, FREDERICK W. SUTTERLE, Jr., a citizen of the United States, residing at Shanghai, China, have invented 5 a new and useful Attachment for Type-Writers, of which the following is a specification.

When a large number of carbon copies are being made by a typewriter there is a possibility of the sheets becoming folded over 10 or passing a second time around the roll of the paper feed; the result of which is that not only is paper wasted but also the time of the operator in rewriting sheets which 15 cannot be used.

The object of the invention is to overcome the above noted defects and the invention consists of novel means for preventing the portion of the sheet written on 20 from being accidentally brought again into position to receive an impression.

The invention further consists of novel features of construction and advantage.

The accompanying drawing illustrates a 25 typical embodiment of the invention but this embodiment is typical only and is susceptible of modifications within the scope of the appended claims.

Figure 1 is a top plan view of an attachment 30 for typewriters embodying my invention. Fig. 2 is a section on line *xx* of Fig. 1. Fig. 3 is a perspective view of the attachment.

Similar numerals of reference indicate 35 corresponding parts in the figures.

Referring to the drawings, 1 designates an attachment for typewriters embodying the invention. The attachment 1 is preferably constructed of an integral piece of 40 material and consists of a body portion 2 having outwardly extending and diverging arms 3 and 4, and said body portion 2 is deflected upon itself to form a groove 5 while its free end is bent outwardly as at 6. The attachment 45 is secured in place on the cross bar 7 of the feed carriage 8 by forcing the attachment against said rod which latter is then received in the groove 5.

The operation is as follows: The sheets 50 of paper are inserted in the usual manner

between the rear paper table 9 and the feed roll 10, and after the impressions have been made thereon the paper passes over the attachment which prevents the carbon sheets from being brought again into feeding engagement with the feed roll. The arms 3 and 4 press against the sheets as they are being fed into the machine and prevent them from being folded over and the carbon paper from becoming misplaced. 60

My invention is especially adapted to be employed with typewriting machines of the Underwood type and can be readily attached to other types of machines by providing a support such as for example a cross 65 bar connected with the feed carriage. The attachment is preferably made of thin flexible metal.

It will be understood that changes may be made within the scope of the invention 70 and the claims.

Having thus described my invention, what I claim as new and desire to secure by Letters Patent, is:

1. The combination with the cross bar of 75 a typewriter feed carriage, of an attachment comprising a thin flexible metal sheet having rearwardly directed arms and a deflected portion forming a groove whereby said attachment may be assembled with said 80 cross bar by forcing the attachment toward the cross bar to cause the latter to become seated in said groove.

2. The combination with a typewriter feed carriage having a feed roller, a rear 85 paper table and a cross bar, of an attachment comprising a thin, flexible, metal sheet having diverging arms at one end, and deflected upon itself near its opposite end to form a groove, and having its free end bent 90 outwardly, said attachment being centrally mounted on said cross bar by forcing it thereagainst and causing it to be received in said groove.

In testimony whereof I hereto affix my 95 signature in presence of two witnesses.

FREDERICK W. SUTTERLE, Jr.
